UNITED STATES PATENT OFFICE.

JAMES W. MACFARLANE, OF GLASGOW, COUNTY OF LANARK, SCOTLAND.

CORE-BAR.

SPECIFICATION forming part of Letters Patent No. 240,745, dated April 26, 1881.

Application filed December 24, 1880. (No model.) Patented in England March 2, 1880.

To all whom it may concern:

Be it known that I, JAMES WRIGHT MACFARLANE, a subject of the Queen of Great Britain and Ireland, and residing at Glasgow, county of Lanark, Scotland, have invented a certain Improvement in Core-Bars, (for which I have obtained a patent in Great Britain, No. 919, March 2, 1880,) of which the following is a specification.

My invention relates to the cores employed when casting iron pipes and similar articles, and in carrying it out the core is formed in a core-box of any suitable known kind, and by preference of dry sand, and the casting operation is, by preference, performed with the molds in a vertical position. The core-bar employed is of a form which, in cross-section, resembles a ratchet-toothed wheel, and rods are placed at the indentations or grooves, such rods being withdrawn, so as to form air-holes after the mold material has been rammed into the core-box. After the casting operation the core-bar is released by turning it slightly.

In the accompanying drawings, Figure 1 is a side elevation of the core-bar with a part supposed to be broken away to reduce the length, and Fig. 2 is a vertical longitudinal section. Fig. 3 is a plan corresponding to Fig. 1, and Figs. 4 and 5 are horizontal or cross-sections, while Fig. 6 is a vertical section.

The core-bar 10 is a hollow casting, the body or main part of which is in cross-section, as seen in Figs. 4 and 5, shaped like a ratchet-toothed wheel. The tooth-like parts are represented as flat; but they might be curved without disadvantage.

When the core-bar 10 is being prepared to have a core rammed upon it, rods 11 are placed in the angles or indentations between the tooth-like ribs or projections, these rods being held at their upper ends by a disk or plate, 12, which is temporarily attached to a square neck, 13, formed at the top of the core-bar. An eye-bolt, 14, is passed through the plate 12 and screwed into a center piece, 17, on the under side, and this center piece is entered into the neck 13 of the core-bar, and is secured therein by a pin or key passed through holes formed in it and in the neck. The rods 11 are formed with small squared heads 15, to which keys

can be applied to turn and loosen them in the sand before withdrawing them, and when the core is being rammed the lower ends of the rods 11 are held in position by passing a wire or string round the bar, or in any other convenient way. In Fig. 4 the core-bar 10, with rods 11 in position, is shown as in the core-box 16 with the mold material rammed in, the core-box 16 represented being of the kind formed by a cast-iron shell slit longitudinally at one part and forcibly closed, and which afterward springs open sufficiently to free the core. When the core has been rammed the rods 11 are withdrawn and form air-holes, the plate 12 being disconnected from the neck 13 of the core-bar and lifted off with the rods. After the casting operation has been effected and when the metal has become sufficiently cool, the core-bar 10 is loosened by turning it round to a slight extent by means of a lever-key applied to its square neck 13, and this movement brings the parts into the relative positions in which they are shown in Fig. 5, the most projecting parts of the ribs being in the air-holes and the broad parts slightly but sufficiently away from the parts of the mold material with which they were in contact, thus allowing the core-bar to be very easily withdrawn.

The inner lower end of the core-bar is provided with the usual lugs or projections, 18, forming parts of bayonet-joints for securing the plate which closes the bottom of the mold-box, or when the pipe is cast with the faucet downward for securing the metal center of the faucet-core.

I claim as my invention--

The combination consisting of the core-bar 10, made with longitudinal ratchet-shaped ribs, and the rods 11, the said rods being placed beside the ribs to form holes into which the projecting edges of the ribs can move when the bar is turned to free it, substantially as set forth.

In testimony whereof I have signed my name to this specification in the presence of two subscribing witnesses.

JAMES W. MACFARLANE.
